UNITED STATES PATENT OFFICE.

WILLIAM DEWHURST, OF METHUEN, MASSACHUSETTS.

ELECTRIC STOPPING DEVICE FOR STRETCHING MACHINES.

Application filed July 5, 1928. Serial No. 290,675.

This invention is a stop motion of the electric type for such cloth handling machines as are known as tentering machines, or it may be used in connection with certain types of 5 mercerizing machines or other machines for stretching cloth laterally.

Such machines are generally from 90 to 100 ft. in length and the cloth is carried along through a series of steam heated pipes in a 10 chamber by endless chains of clips or pincers which move along and then around and back to the point of beginning. The clips or pincers are so arranged that their jaws automatically seize the edges of the cloth at the 15 receiving end of the machine and as they move along, move away from each other so as to stretch it while passing between the hot pipes. After they have traversed the main length of the machine, the pincer jaws are 20 automatically caused to open when they move around a wheel or pulley at the delivery end, releasing the cloth at a given point, which point is where they begin to move away from the general line of motion.

25 Occasionally, because of a flaw in the cloth or because the clips or pincers do not let go at the right time, a piece of cloth is torn out and carried along around a delivery pulley causing very serious damage to the machinery.

When a substantial piece of cloth is so carried into the pipe chamber, it is a hot, dangerous, and disagreeable job to extricate it and causes a delay of 45 minutes to an hour or 35 more with the consequent loss of production.

This device is an electric switch positioned in a switch circuit and having a handle or arm in such position close to the pincers but not touching them so that if a bunch of cloth 40 is carried around, such bunch will strike the handle and throw the switch which preferably breaks, although it may be designed to make, the switch circuit whereby a suitable electro-magnet will operate a stopping lever 45 to stop the whole machine.

Preferably I use an electric driving circuit of the three phase or one phase type and interpose in this circuit as a stopping and starting lever for the machine, a switch 50 which has its operating or movable member controlled by such electro-magnet.

This magnet however might operate a shifting lever for shifting a belt, clutch or other similar device to stop the machine.

In the drawings, Fig. 1 is a diagrammatic plan view of the device applied to a tentering machine driven by a three phase A. C. driving circuit. 55

Fig. 2 is an elevation of one of my preferred form of automatic stopping switches 60 as viewed from the point X in Fig. 1.

Fig. 3 is an elevation as from the left of Fig. 2.

Fig. 4 is a sectional detail of the various switches, shown diagrammatically applied to 65 a single phase driving circuit.

Fig. 5 is a view similar to Fig. 2 of a modified form of switch.

Fig. 6 is a view partly in section from the 70 left of Fig. 5.

In the drawings, A and B represent the cloth carrying or stretching mechanism between which the cloth C passes.

A and B are each made up of endless chains 75 of clips or pincers, those shown in the drawings including a top jaw 20 and a bottom jaw 21.

These endless chains are caused to travel respectively around the pulleys 10 and 11 for 80 A and 12 and 13 for B.

By means of suitable devices which are old, the pincers are caused to seize the edges of the cloth at 23 and 24 and to hold it firmly as it travels along at 14 and 15 until it reaches the points at approximately 25 and 26 where 85 by means of suitable plow or release mechanism 27 or 28 they are supposed to let go allowing the cloth to continue as at 29 and to be rolled up or handled by suitable other mechanism. 90

Where, as shown at 40, a strip of the cloth is ripped off, and either is not released by the pincers or gets tangled up with them so that it is carried along as around one of the delivery pulleys 10 or 12, serious delay and 95 damage results.

In such machines as now constructed, there are usually two or more stopping devices whereby the machine can be stopped by hand in case of accident and to avoid trouble. 100

Where an electric motor such as R is used for the main drive, there is interposed in the circuits therefor, which are indicated by Y, 154 and 156, a controller O by which the speed of the motor is controlled and by which the circuit can be opened and the motor stopped.

I interpose a switch M between 154 and 156

which ordinarily is kept closed by the electro-magnet 53 interposed in the switch circuit indicated by P.

The moving members 55 of switch M are pivoted at 54, 54, 54 as shown in Fig. 1 and when closed by magnet 53 close the circuit through contacts 56 and wires 156. This is the normal operating position of the parts while the machine is running, the switch being of the circuit breaker type.

In Fig. 4, the parts are the same except that there is only one movable switch member 55 and the switch circuit is not a three phase one.

When the switch circuit P is broken as by 15 means of the hand operable push button switch F at the other end of the machine or by the operation of my automatic switch indicated by G, the spring 155 opens the main circuit, stops the motor R and therefore the 20 machine.

This switch circuit obtains current as from a battery 57 from which extend the wires 59 and 58. Wire 59 passes around magnet 53 and thence through wire 50 to a hand push 25 button switch indicated by F located at the other or receiving end of the machine. This switch enables the operator who may be at that end to open or close the switch circuit P thus stopping the machine from the other 30 end. This switch F preferably is of the push button type which can be opened or closed and will stay in the desired position as by means of pin 167 which can be pushed down through hole 166 and turned under cover 68, 35 or turned and released through hole 166.

The conductor 51 from F enters one end and the conductor 58 from battery 57 enters the other end of the automatic switch G.

The contact parts of automatic electric 40 switch G and hand switch F are substantially the same as each includes a box such as 69 having a cover 68, there being openings through which pass the insulated contact wires such as 50, 51 to the contacts 161 and 45 163 insulated from the box by insulation 162 and 164.

61 is a hollow guide post which sticks up from the bottom of box 69 and serves as a guide for the capped cylindrical push button 50 60 preferably of insulating material and which carries the contact disk 160. When 60 and 160 are pushed down as shown in the full lines, the current passes through 160 from the contacts 161 and 163 in each case 55 the circuit being to that extent closed but when released, the action of spring 165 moves both up to the dotted line positions shown in Figs. 3 and 4 and the circuit is opened.

Switch F is normally closed and locked in 60 place by a pin 167 and switch G is normally also closed and locked in position by means of the rocking arm 63 pivoted to an arm 264 attached to box 69 and having at one end 65 an adjustable thumb nut which engages the 65 top of contact 60, its other end 66 resting or-

dinarily on the top end 70 of a trigger arm which is pivoted to the frame at 71. This trigger arm extends downward at 72 in the form of a tail or operating handle which is in such position that it will be struck by any 70 bunch of cloth such as 40 which may become caught in the traveling clips or pincers and get by the releasing devices 27 and 28.

When so struck, the trigger arm will be carried to the dotted line position shown in 75 Fig. 2 allowing the rocking arm 63 to be pushed up by spring 165 to the position shown by the dotted lines in Fig. 3 thus breaking the circuit and contact between disc 160 and contacts 161 and 163.

As shown in Figs. 5 and 6, instead of the trigger arm 70, 72 and the rocking arm 62, one end of which 66 rests on 70, I may combine the two as an automatic switch R.

The conductor 51 enters a plate 87 of insulating material at 86 which has a contact insert 89 in a position to be engaged by spring-pressed finger 85 carried by switch arm 80 pivoted at 81 and connected with the conductor 58 its other end or handle 82 being in the same position as the tail or operating handle 72.

When this tail 82 is struck by a piece of cloth such as 40 and moved to the dotted line position, the switch circuit P is broken and the machine is stopped.

Preferably there are two of the automatic stopping switches such as G and G₂ or R, each one just beyond the clip releasing devices 28 and 27, and one or more hand stopping switches such as F, all in a switch circuit which is normally kept closed.

It is obvious that arm 55 might be, or might be replaced by, a shipper handle or by any other drive mechanism stopping device.

I claim:

1. In a cloth stretching machine of a type wherein the cloth is carried along between endless chains of pincers, which pincers move around and away from the point where they normally release the cloth; the combination of two automatic electric stopping switches each positioned beyond said releasing point and each having a handle so pivoted that it will be struck and thrown by any substantial piece of cloth which is carried away and around from said releasing point; a hand operable switch positioned at a third point on said machine; the automatic switches and said hand-switch being interposed in a switch circuit from a source of electric power, said circuit also passing through an electro-magnet which has an armature the operating member of a device for stopping and starting the cloth handling machine, the parts being so arranged that the machine is stopped when the switch circuit is open.

2. In a cloth stretching machine of the type wherein the cloth is carried along between endless chains of pincers, which pin-

cers move around and away from the point where they normally release the cloth; the combination of an automatic electric stopping switch having a handle so pivoted that it will be struck and thrown by any substantial piece of cloth which is carried away and around from said releasing point; said switch being interposed in a switch circuit from a

source of electric power, said circuit also passing through an electrically operative stopping device, such switch, source of electric power and stopping device being so arranged that the machine is stopped when the circuit is open. 10
